(57) CLAIM

The ornamental design for a truck bed tent, as shown and described.

DESCRIPTION

FIG. 1 is a perspective view of the truck bed tent showing an implementation of the new design, with tent windows and a door of the tent body shown in dashed lines;

FIG. 2 is a rear view thereof;

FIG. 3 is a front view thereof;

FIG. 4 is a top view thereof; and,

FIG. 5 is a side view thereof.

The portions shown in broken lines form no part of the claimed design.

1 Claim, 3 Drawing Sheets
